199,823

FILM UNIT FOR A PHOTOGRAPHIC COPYING APPARATUS

Ralph M. Vigna, Rochester, N.Y., assignor to Eastman
Kodak Company, Rochester, N.Y., a corporation of
New Jersey

Filed Dec. 16, 1963, Ser. No. 77,815

Term of patent 14 years

(Cl. D61—1)

FIGURE 1 is a front perspective view of a film unit for a photographic copying apparatus showing my new design;

FIGURE 2 is a left side elevational view;

FIGURE 3 is a right side elevational view;

FIGURE 4 is a top plan view;

FIGURE 5 is a rear elevational view; and

FIGURE 6 is a bottom view thereof.

I claim:

The ornamental design for a film unit for a photographic copying apparatus, as shown.
